UNITED STATES PATENT OFFICE.

JAMES K. MURPHY, OF WASHINGTON, DISTRICT OF COLUMBIA.

EXTENSION-BRACE FOR EXCAVATIONS.

SPECIFICATION forming part of Letters Patent No. 606,631, dated June 28, 1898.

Application filed September 4, 1897, Serial No. 650,647. (No model.)

To all whom it may concern:

Be it known that I, JAMES K. MURPHY, a citizen of the United States, residing at Washington city, in the District of Columbia, have 5 invented certain new and useful Improvements in Extension-Braces for Excavations; and I do hereby declare the following to be a full, clear, and exact description of the invention, such as will enable others skilled in 10 the art to which it appertains to make and use the same.

My invention relates to certain new and useful improvements in extensible braces for supporting the walls of excavations, such as 15 sewers, tunnels, &c.

The objects of my invention are to provide a simple and secure brace embodying comparative lightness and great strength and also economy in the use of timber; and with 20 these ends in view my invention consists in forming the brace of parallel or camber timbers having at suitable predetermined localities pack-blocks intervening between the timbers and securely held in place, and the 25 timbers secured by bolts passing through the timbers and pack-blocks and providing one end of the brace with any suitable shoe and the opposite end with a shoe and screw, all as will be hereinafter more fully set forth.

In order that those skilled in the art to which my invention appertains may know how to make and use the same, I will proceed to describe the construction and method of using the same, referring by letters to the accompanying drawings, in which—

Figure 1 is a perspective view of one of my improved braces. Fig. 2 is a similar view showing the timbers secured in such manner as to produce a double camber; and Fig. 3 is 40 a view similar to Fig. 1, but showing the side timbers composed of two or more sections.

Similar letters of reference denote like parts in the several figures of the drawings.

A A represent two timbers, usually three 45 by twelve inches and of any length desired, according to the locality at which it is desired to use the same. The two timbers A A are separated by pack-blocks B, arranged at each end and at any suitable number of 50 points intermediate of the end, as clearly shown. The timbers and pack-blocks are secured rigidly together by screw-bolts C and

nuts D, with washers E arranged, as shown, between the heads of the bolts and one timber and between the securing nuts D and the 55 other timber.

One end of the brace is provided with a shoe F, having spurs G or corrugations at its sole and made in box form or with a socket to receive the end of the brace, to which it 60 is rigidly secured by the bolts, which also secure in place the end pack-blocks. The opposite end of the brace is provided with a casting H, which is secured in place in a similar manner to the shoe F by bolts passing 65 through the casting, timbers, and end pack-block. The end of the casting H is bored centrally to permit a screw I to freely traverse through it, and the end pack-block is similarly bored for a like purpose. 70

J is a shoe connected by a ball or universal joint with outer end of the screw I, and K is a hand-nut traveling upon the thread of the screw I and adapted to bear against a suitable platform or collar surrounding the screw- 75 channel in the casting H in order that the screw I, carrying the shoe J, may be extended outwardly or retracted by the rotation of the hand-nut for obvious purposes.

It will be seen that if the brace be made, as 80 is customary, of solid timber it becomes necessary to bore the end to a depth sufficient to accommodate the extreme inward movement of the screw, while according to my construction of double timbers and pack-blocks it is 85 only necessary to bore through the pack-block, because the screw is free to move into the space between the timbers.

Another advantage of my improved construction rests in the fact that I am enabled 90 to secure substantially the same strength that is provided by a solid brace, with less weight and at decreased cost of manufacture. For instance, with two three by twelve inch timbers and three-inch intervening pack-blocks 95 I secure a brace having all the advantages of a solid brace nine by twelve inches and with a crushing resistance equal to a solid timber sixteen by sixteen inches. Still another advantage flows from the circumstance that by 100 the employment of the pack-blocks intervening between the double timbers or stretchers the latter may be made in sections and from timber of less length than would be required

in the use of a solid brace. By reference to Fig. 3 it will be seen that the upper side of the brace is composed of three sections and the lower side of two sections so arranged as 5 to break joints and rigidly secured to pack-blocks in such manner as to produce a continuous brace having substantially as much strength and stiffness as a solid brace. As lumber of a given width and thickness increases in price according to increase in length, it will be readily seen that my improved construction involves great economy.

In the construction shown at Fig. 1, where-in the side timbers are parallel, the pack-blocks are arranged flat; but when it is desired to produce a brace with a double camber the pack-blocks are arranged lengthwise and may be of any length, according to the camber desired.

It will be understood that the construction shown in the braces may be advantageously employed also in pack-posts for bridge-building.

What I claim as new, and desire to secure 25 by Letters Patent, is—

1. An extensible brace for excavations comprising two wooden side beams separated by pack-blocks at each end and at points intermediate of the ends, said pack-blocks secured in position by bolts and nuts as shown, a shoe 30 F at one end and a casting II, screw I and nut K at the opposite end, substantially as and for the purpose set forth.

2. An excavation - brace comprising two wooden side beams A, A confined at one end by a metal shoe F and at the opposite end by a casting II a screw I and nut K, pack-blocks between the ends of the side timbers, and intermediate pack-blocks B of greater length than the end blocks the blocks being secured 40 by bolts and nuts, whereby a double camber is produced, substantially as and for the purpose set forth.

In testimony whereof I affix my signature in presence of two witnesses.

JAMES K. MURPHY.
